SHUTTLE CHANGING LOOM

Verner Lindsjo, Hopedale, Mass., assignor to
Draper Corporation, Hopedale, Mass., a corpora-
tion of Maine

Application February 23, 1933, Serial No. 658,010

9 Claims. (Cl. 139—230)

The present invention relates to shuttle changing looms, and has more particular reference to the mechanism by which the shuttle changing operation is initiated.

5 In looms of the type involved, the running shuttle is automatically removed, and another shuttle automatically inserted in the shuttle box, when the filling supply in the running shuttle becomes substantially depleted, such shuttle changing operation being initiated by means under control of a filling feeler. The shuttle changing operation leaves the newly inserted shuttle entirely within the shuttle box but spaced inwardly away from the picker. Since the action of the 10 picker stick is not varied at the time of changing shuttles, the spacing of the shuttle away from the picker results in the first pick thereafter being weaker than usual, which in turn results in the shuttle arriving late the opposite side of the loom 15 and, occasionally, not entering fully and completely into the proper position in the shuttle box. This abnormal action of the shuttle is disadvantageous, principally because the feeler may strike the shuttle wall and thus be induced to unnecessarily call for replenishment.

A further disadvantage of certain types of shuttle changing looms is that two successive transfers, or indications for transfer, may result in the running filling being cut and forming a 20 partial pick in the cloth.

It has been proposed heretofore to remedy the first mentioned defect in the operation of shuttle changing looms in various ways, as by providing shuttle pushers or placers for pushing the newly 25 inserted shuttle up against the picker. However, such devices are necessarily complicated and expensive and still do not overcome the second objectionable feature above mentioned.

I have discovered that by merely positively insuring that a second shuttle changing operation 30 cannot be initiated within one pick after the completion of one such operation the bad effects of the first mentioned defect will be eliminated, at least from a practical standpoint, and the second 35 will be completely overcome.

Accordingly, it is the principal object of my invention to provide, in a shuttle changing loom having a filling feeler and means controlled thereby for initiating operation of the shuttle changing 40 mechanism, means for positively preventing initiation of a second shuttle changing operation within one pick after completion of one such operation.

Further objects of the invention will, in part, 45 be hereinafter more specifically enumerated or

will become obvious as the description proceeds.

The preferred embodiment of my invention is illustrated on the accompanying drawings, of which:

Fig. 1 is a perspective view of so much of a 60 loom as is necessary to illustrate the applicability of my invention thereto;

Fig. 2 is a plan view of certain mechanism appearing at the left part of Fig. 1;

Fig. 3 is a view in elevation of the mechanism 65 appearing in Fig. 1, but showing the parts in the relative positions they assume at a different time in the cycle of operations; and

Fig. 4 is a view similar to Fig. 3 but showing the 70 parts in still a different position.

The loom to which my invention has been applied has the parts thereof supported by a usual frame, of which only the breast beam 1 is shown. Of such parts, I have shown the lay 2 mounted on swords 3 for oscillation toward and from the front of the loom, i. e. toward and from the breast beam 1, and have also shown the reed 4, left and right hand shuttle boxes 5 and 6 respectively, a picker stick 7 (of which two are employed), a filling feeler 8 at one side of the loom, a shuttle changing mechanism, and means for initiating 80 operation of the shuttle changing mechanism under control of the filling feeler. Other usual parts of the loom need not be herein illustrated or described as they are well known in the art and 85 form no part of the present invention.

The particular filling feeler illustrated is of the side slipping type provided with a blade 9 having a tip adapted to enter a slot 10 in the front box plate of the shuttle box 5, to feel the filling 90 in the shuttle 11, the tip slipping upon a bare, or nearly bare, filling carrier in the shuttle and serving thereby to indicate that the filling supply is substantially exhausted. This feeler is identical with that shown in Brown and Repass 95 Patent 1,593,426, granted July 20, 1926, but any other suitable feeler may be used if so desired.

Side slipping of the feeler stem results in the 100 operation of certain connections herein comprised of a rod 12 pivotally connected to a latch 12'. The latch is pivotally suspended from a link 13, after the manner of said Brown and Repass patent, and is weighted to normally hang out of the path of the usual weft hammer 14. The weft hammer is constituted by a bell crank lever pivoted on a stud 15 in the loom frame and actuated by a cam 16 on cam shaft 17 which is driven at the 105 rate of one complete revolution for each two picks of the loom.

The cam 16 is designed and timed to start the 110

weft hammer on its forward movement just before the lay reaches front center on the pick when the shuttle is boxed on the feeler side of the loom. If the feeler does not operate at this time, the 5 weft hammer merely reciprocates idly in the forked end 18 of the link 13. However, if the feeler does operate it will push rod 12 endwise and thus tilt latch 12' into the path of the weft hammer, whereupon continued forward movement of the latter will push link 13 forwardly.

The forward end of link 13 is connected to the upper end of an upstanding arm 19 fixed to the change shaft 20, which extends widthwise of the loom and is rotatably supported in bearings 21, 21 15 on the breast beam 1. Forward movement of the link 13 will serve to oscillate shaft 20, which in turn raises arm 22 on the shaft and, through link 23, raises dagger 24 into the path of a bunter, not shown, on the right hand lay sword, the raising 20 of dagger 24 constituting the final step in the initiation of the shuttle changing operation.

The shuttle changing mechanism is but fragmentarily illustrated. It is positioned entirely on the opposite side of the loom from the filling 25 feeler and includes a magazine 25 containing a reserve supply of shuttles 26, 26 movable front and rear box plates 27, 28 in the shuttle box 6, operating arm 29, a shuttle pusher concealed beneath cover plate 30, and certain other mechanism not shown. The shuttle changing mechanism is not of the present invention but is disclosed and claimed in my prior Patent Number 1,850,304, granted March 22, 1932, to which reference may be had for a more complete 30 disclosure of this particular mechanism. It is herein noted, however, that such mechanism changes shuttles when the lay is at front center and no part of the loom stops while the change is being made.

40 It will be noted that certain stopping mechanism including shipper handle 31, shipper lever 32 and stop rod 33 are shown at the left of Fig. 1. This mechanism, while forming an essential part of the particular loom shown, does not operate 45 directly with the mechanism forming the essence of the present invention and is illustrated merely to show one good relative disposition of the parts on the breast beam.

Before proceeding with a detailed description of the remaining parts of the illustrated embodiment 50 of my invention, I wish to explain the meaning of the word "pick" as it is used herein. This word has a rather flexible meaning, but is herein employed to denote one complete cycle of movement 55 of the lay, starting with the lay part way back on its rearward movement, at which time the picker stick is just starting its inward sweep. Thus, the filling feeler acts when, during one pick, the lay is at front center, while the shuttle changing operation 60 occurs on, or during, the subsequent pick.

The shuttle changing operation occurs while the shuttle is in the right hand box, and the newly inserted shuttle is not fitted snugly against the picker on picker stick 7. The next pick will 65 accordingly be abnormal in that the shuttle will not be thrown with normal force and will arrive late in the left hand shuttle box. The abnormality of the action of the shuttle may even be sufficient that the shuttle will not enter completely into the shuttle box 5 and the feeler tip 70 will strike, and slide upon, the wall of the shuttle. Thus, a second shuttle changing operation is initiated the very next pick after completion of one such operation. If the shuttle changing 75 mechanism be of the type that can operate re-

peatedly upon consecutive returns of the shuttle to the replenishing side of the loom, a needless change of shuttles will occur. Even though the shuttle changing mechanism is of a type that cannot thus change shuttles a second time the operation will be initiated and more or less of the parts will go through the motion of changing, and the running filling will be cut. It is to the elimination of the possibility of initiating a second shuttle changing operation within one 80 pick after the completion of one such operation that my invention pertains.

To this end, I have provided means for rendering the change initiating mechanism inoperative during the first pick after completion of a shuttle 85 changing operation. The particular form of such means which I prefer includes a locking member 34 mounted on link 13 and bodily movable thereon to and from locking position. The member 34, as shown, consists of a flat plate having a rearwardly and downwardly extending nose 35 and a slightly inclined abutment surface 36. A bolt 37, fixed in the locking member, passes through a horizontally extending slot 38 in the link 13. A bolt 39 in the link 13 passes through a curved 90 slot 40 in the locking member, the curvature of the slot providing two definite positions for the locking member. That is, when member 34 is in its normal, forward position, as shown in Figs. 1 and 4, the curvature of slot 40 serves to retain the member in this position, and likewise when the member is in rearward locking position, as shown in Fig. 3, the curvature of the slot 40 again serves to retain the member in position.

A fixed stop, conveniently constituted by an 95 adjustable screw or bolt 41 threaded into an upstanding arm on bracket 42, serves to move the locking member to locking position. An inclined face 43 on bracket 42 cooperates with a similarly inclined face 44 on link 13 to raise the latter 100 coincidentally with its forward movement, for a purpose presently to be described.

The operation of the above described mechanism is as follows:

As the lay approaches front center, with the 105 shuttle in the left hand box 5 and the filling supply substantially exhausted, the feeler tip will slide upon the filling carrier and push on rod 12 to thereby tilt latch 12' up into the path of the weft hammer 14. At this time, the weft hammer 120 is just starting its forward movement and it therefore engages latch 12' and pushes link 13 and arm 19 forwardly, thus rotating change shaft 20 and initiating operation of the shuttle changing mechanism in a manner that need not be 125 further discussed.

Early in the forward movement of link 13, the inclined faces 43, 44 cause the link to be raised about its pivotal connection with the arm 19. The weft hammer 14, through engagement with 130 latch 12', prevents the latter from rising with the link 13 and thus partially returns the latch to its normal lower position. At this time the parts occupy the relative positions shown in Fig. 4, from which it will be noted that abutment 135 surface 36 is just contacting the fixed stop screw 41. The lay, at this time, is approaching back center and the shuttle has been thrown toward the right hand shuttle box 6.

Continued forward movement of the weft 145 hammer and link 13, while the locking member 34 is held stationary by stop screw 41, will result in relative movement of the locking member to locking position wherein bolt 39 is at the extreme forward end of slot 40 and nose 35 projects 150

- over latch 12' in sufficient proximity to the latter to lock the latch, rod 12 and feeler stem 9 out of operation. Shortly after the completion of the forward movement of the weft hammer 5 the lay reaches front center again, and the shuttle changing mechanism ejects the shuttle and inserts a new one. Then the lay starts rearwardly, marking the completion of the second pick discussed.
- 10 When the lay is approximately half way back on the rearward movement the shuttle is thrown to the left hand box. Simultaneously the weft hammer moves to its rearward position where it dwells until just before the lay again approaches front center. During the whole of this 15 pick, which is the third discussed and the first after completion of the shuttle changing operation, the locking member 34 occupies locking position as shown in Fig. 3. Thus, at no time 20 during this pick is it possible to initiate a second shuttle changing operation. However, as soon as this pick is completed (and the lay moves rearwardly) the forward movement of the weft hammer will result in the nose 45 thereof engaging 25 bolt 37 (see Figs. 2 and 3) and moving the locking member 34 forwardly away from locking position, link 13 remaining stationary at this time. The parts are thus reset to their normal positions.
- It is noted particularly that the "preventing" 30 means described is independent of the condition of the filling supply in the newly inserted shuttle, and this is desirable for the reason that, as above noted, even though the filling supply be substantially depleted a call for a shuttle changing operation 35 at this time is not desirable as it would result in the running filling being cut. I have not illustrated the cutting mechanism or the manner in which the same would be operated as such are well known in the art and constitute 40 merely one of the necessities for, rather than a constituent part of, my invention. A suitable form of thread cutting mechanism is shown in my prior Patent 1,850,305, granted March 22, 1932.
- I do not wish to be limited to the exact form 45 of my invention herein shown, as many changes may be made therein and I believe that I am the first inventor of the invention as broadly as defined in the appended claims.
- I claim:
- 50 1. A shuttle changing loom having a lay and a filling feeler, means for automatically changing shuttles while the lay is at front center, means for initiating operation of said shuttle changing means when said filling feeler detects substantial exhaustion of the filling supply, and means for preventing operation of said filling feeler during the first pick after a shuttle changing operation, regardless of the condition of the filling supply 55 in the newly inserted shuttle.
2. A shuttle changing loom having a side slipping filling feeler, means for automatically changing shuttles, means for initiating operation of said shuttle changing means when said filling feeler detects substantial exhaustion of the filling supply, and means operating independent of the condition of the filling supply for locking 60 said feeler against side slipping movement during the first pick after a shuttle changing operation.
- 70 3. A shuttle changing loom having a lay and a filling feeler at one side thereof, means positioned at the opposite side of the loom from said filling feeler for automatically changing shuttles while the lay is at front center, means for initiating operation of said shuttle changing means 75 when said filling feeler detects substantial exhaustion of the filling supply, and means for preventing two successive operations of said shuttle changing means on consecutive movements of the shuttle to the replenishing side of the loom, said last mentioned means operating independent of the condition of the filling supply in the shuttle. 80
4. A shuttle changing loom having a side slipping filling feeler at one side thereof, means positioned at the opposite side of the loom from said filling feeler for automatically changing shuttles, means for initiating operation of said shuttle changing means when said filling feeler detects substantial exhaustion of the filling supply, and means operating independent of the condition of the filling supply for locking said feeler against side slipping movement during the first pick after each shuttle changing operation. 85
5. A shuttle changing loom having a side slipping filling feeler at one side thereof, means positioned at the opposite side of the loom from said filling feeler for automatically changing shuttles, means for initiating operation of said shuttle changing means when said filling feeler detects substantial exhaustion of the filling supply, a locking member movable to and from locking position where it prevents initiation of operation of said shuttle changing means, means for moving said member to locking position, and means for moving said member from locking position when the first pick after each shuttle changing operation has been completed. 90
6. A shuttle changing loom having a filling feeler at one side thereof, means positioned at the opposite side of the loom from said filling feeler for automatically changing shuttles, means for initiating operation of said shuttle changing means when said filling feeler detects substantial exhaustion of the filling supply, a locking member carried by said second mentioned means and movable to and from locking position where it renders said filling feeler inoperative, and a fixed stop for engaging said locking member and positioning it in locking position each time a shuttle 100 changing operation is initiated. 105
7. A shuttle changing loom having means at one side thereof for automatically changing shuttles, a filling feeler at the opposite side of the loom from said shuttle changing means, and means for initiating operation of said shuttle changing means when said filling feeler detects substantial exhaustion of the filling supply, said second mentioned means including a change shaft 110 extending widthwise of the loom, an arm on said shaft, a link connected to said arm for moving the latter, connections between said feeler and said link, a locking member mounted on said link and bodily movable thereon to and from locking position, where it renders said connections inoperative, and a fixed stop engaging said member, upon movement of the said link, for moving said member to locking position. 115
8. A shuttle changing loom having means at one side thereof for automatically changing shuttles, a filling feeler at the opposite side of the loom from said shuttle changing means, and means for initiating operation of said shuttle changing means when said filling feeler detects substantial exhaustion of the filling supply, said second mentioned means including a change shaft 120 extending widthwise of the loom, an arm on said shaft, a link connected to said arm for moving the latter, connections between said feeler and said link, a locking member mounted on said link 125 and bodily movable thereon to and from locking position, where it renders said connections inoperative, and a fixed stop engaging said member, upon movement of the said link, for moving said member to locking position. 130
9. A shuttle changing loom having means at one side thereof for automatically changing shuttles, a filling feeler at the opposite side of the loom from said shuttle changing means, and means for initiating operation of said shuttle changing means when said filling feeler detects substantial exhaustion of the filling supply, said second mentioned means including a change shaft 135 extending widthwise of the loom, an arm on said shaft, a link connected to said arm for moving the latter, connections between said feeler and said link, a locking member mounted on said link 140 and bodily movable thereon to and from locking position, where it renders said connections inoperative, and a fixed stop engaging said member, upon movement of the said link, for moving said member to locking position. 145
10. A shuttle changing loom having means at one side thereof for automatically changing shuttles, a filling feeler at the opposite side of the loom from said shuttle changing means, and means for initiating operation of said shuttle changing means when said filling feeler detects substantial exhaustion of the filling supply, said second mentioned means including a change shaft 150 extending widthwise of the loom, an arm on said shaft, a link connected to said arm for moving the latter, connections between said feeler and said link, a locking member mounted on said link 155 and bodily movable thereon to and from locking position, where it renders said connections inoperative, and a fixed stop engaging said member, upon movement of the said link, for moving said member to locking position.

and bodily movable thereon to and from locking position, where it renders said connections inoperative, means for moving said member to locking position each time a shuttle changing operation is initiated, and means for moving said member away from locking position during the second pick after completion of each shuttle changing operation.

9. A shuttle changing loom having means for automatically changing shuttles, a side slipping filling feeler, and means for initiating operation of said shuttle changing means when said feeler detects substantial exhaustion of the filling sup-

ply, said second mentioned means including a change shaft, an upstanding arm on said shaft, a link connected to said arm for moving the latter, a locking member mounted on said link and bodily movable thereon to and from locking position, where it locks said feeler against side slipping, means for moving said member to locking position each time a shuttle changing operation is initiated, and means for moving said member away from locking position during the second pick after completion of each shuttle changing operation.
